DRILLING APPARATUS

Filed Oct. 17, 1925

UNITED STATES PATENT OFFICE

JOSEPH S. MITCHELL, OF CHICAGO, ILLINOIS, ASSIGNOR TO SULLIVAN MACHINERY COMPANY, A CORPORATION OF MASSACHUSETTS

DRILLING APPARATUS

Application filed October 17, 1925. Serial No. 63,147.

This invention relates to drilling apparatus and more particularly to a rotary drilling apparatus of the oil or gas well type.

A rotary drilling apparatus is particularly adapted to use in drilling subterraneous formations of relatively soft character. The cutting tool or bit usually is fed to the work by gravity. However, when the weight of the rod line is excessive a usual hoisting mechanism is utilized to relieve a portion of the weight from the cutting bit, the hoisting cable being adapted for connection to a usual water swivel carried at the upper end of a usual fluted grief stem. The cutting tool and rod line are adapted to be rotated by what is commonly called a rotary machine or revolving table which is placed on suitable supports on the ground or on the derrick floor directly over the hole. Furthermore, the grief stem to which the rod line is connected passes through a suitable central opening in the rotary table and the latter is adapted to be driven from a usual driving engine, the latter also usually being utilized for driving the hoisting mechanism.

Under certain conditions, for instance if the subterraneous formations encountered by the cutting bit are of relatively hard material or if a core of the bedding strata is desired to be obtained, it has been found highly desirable to remove the usual rotary cutting bit from the rod line and to substitute therefor a core barrel, the latter preferably being provided with a usual rotary diamond cutting bit. However, when a diamond cutting bit is utilized it has been found impractical to feed the bit by means of the usual rotary gravity feed, the diamonds chipping or breaking under the excessive strains and shocks encountered.

The primary object of this invention is to provide an improved means for feeding and controlling the cutting bit and rod line of a rotary oil or gas well drilling apparatus whereby the feed may be perfectly regulated. Another object of this invention is to provide an improved, inexpensive, simple, and thoroughly reliable hydraulic feeding means for a rotary drill. Still another object of this invention is to provide an improved auxiliary

hydraulic feeding means for a rotary drill which acts directly on the "fast line" of the usual hoisting tackle. These and other objects of my invention will, however, subsequently more fully appear.

This invention in one of its aspects comprises an improved feeding and controlling mechanism for the rotary drill rods when a diamond cutting bit is utilized and such means preferably acts directly on the "fast line" of the hoisting cable which extends between the usual hoisting drum and the upper end of the rod line. Preferably, this feeding and controlling means comprises a hydraulic hoisting and lowering device, in this instance a hydraulic cylinder suitably rigidly mounted on the derrick floor or jack posts of the derrick. This cylinder has a piston therein which may carry a cable guiding sheave which preferably acts directly on the "fast line" of the hoisting cable as will hereinafter more fully appear, the main purpose of this feeding and controlling device being to relieve excessive weight from the cutting bit and to provide an improved control therefor.

In the accompanying drawings I have shown for purposes of illustration one form which my invention may assume in practice.

In these drawings,—

Fig. 1 is a somewhat diagrammatic view showing the manner in which the rotary equipment is used in oil or gas well drilling when a rotary diamond bit is employed, the auxiliary feeding device being shown in a plurality of positions.

Fig. 2 is a central longitudinal sectional view through the auxiliary hydraulic feeding and controlling device.

As shown in the drawings 1 indicates as an entirety the well derrick which may of course be of any suitable kind or construction and having a floor 2 by which a usual revolving table 3 is supported whereby the cutting bit and rod line are rotated when in operation. It will herein be noted that carried on the derrick floor 2 is a suitable driving engine, not shown, which is adapted to drive through chain and sprocket connections 4 a usual hoisting drum 5 upon which a cable 6 is adapted to be wound. Furthermore, the

revolving table 3 is adapted to be driven from the engine by means of a suitable chain and sprocket connection 7 in a well known manner. Extending through the revolving table 3 of the rotary machine is the usual squared or fluted drill or grief stem 8 which has attached thereto in any suitable manner at its upper end a usual water swivel 9 having a pivoted lifting bail 10. This drill stem 8 is 10 adapted to be suitably attached by means of a tool joint 11 to a string of hollow drill pipes or rods 12. It will also be noted that carried on the derrick floor is a usual fluid pump 13 which is adapted to pump fluid under pressure to the cutting bit through hose connections 14 and 15, the latter being suitably attached to the water swivel 9. As illustrated, the cable 6 passes from the hoisting drum 5 around the bottom of a guide sheave 16 journaled within brackets 17 carried by the foundation of the well derrick. The "fast line" 20 of this cable extends from the sheave 16 upwardly around a usual crown block 18 and then downwardly in a multi-strand connection around a pulley block 19, the latter carrying the usual hoisting hook 20. The portion of the hoisting cable on which the feeding device acts is called the "fast" line as that part of the cable moves faster than the portion which is threaded through pulley blocks, there being a substantial speed reduction 30 between the "fast" line and a hoisting hook 20. It will herein be noted that the rotary drilling apparatus shown is merely for purposes 35 of illustration and that any desired hoisting and driving arrangement may be utilized in place of that shown.

In my improved construction it will herein be observed that the usual rotary cutting bit has been removed from the rod line 12 and a core barrel 21 substituted therefor, the core barrel carrying at its lower end a usual cutting bit 22 herein of the well known diamond rotary type. To obtain a perfect regulation of the feed of the diamond bit 22 I have combined with the rotary rig in a novel manner a hydraulic feeding and controlling device generally designated 23 which herein comprises a substantially horizontal cylinder 24 which may be of any desired size and having secured thereto at its opposite ends suitable cylinder heads 25 and 26, respectively. As shown, the cylinder 24 has formed thereon laterally projecting supports 27 which are suitably bolted as at 28 to a transversely disposed supporting member 29 carried by upright members supported by the derrick floor, thus forming a rigid and stable support for the feeding device. As illustrated, disposed within the cylinder 24 is a piston 30 having secured thereto a piston rod 31 which passes from the front of the cylinder through a suitable stuffing box 32. In accordance with this invention the piston rod 31 has secured thereto in a suitable manner

at its forward end a sheave or pulley 33 which is adapted to engage the "fast line" of the usual hoisting tackle. Suitably connected to the fluid pump 13 by means of the pipe connection 14 is a pipe connection 34 70 which is adapted to conduct through branch connections 35 and 36 fluid under pressure, herein water, to the opposite ends of the cylinder 24 under the control of suitably manually operable valves 37 and 38. Disposed on the opposite side of the cylinder 24 and controlled by valves 39 and 40 is a fluid by-pass connection 41 while branching therefrom under the control of a manually operable valve 42 is a drain pipe 43. 75

In the operation of my improved hydraulic feeding and controlling device it will herein be noted that when it is desired to use a core barrel and diamond bit in the place of the usual rotary cutting tool, the "fast line" of the 80 hoisting cable 6 is passed around the guide sheave 33 and the hoisting hook 20 is connected to the lifting bail 10 of the water swivel 9. The core barrel 21 is then lowered into the hole under control of the usual hoisting drum 90 5. When the diamond bit 22 assumes a position adjacent the bottom of the hole, water under pressure is forced from the pump 13 through the pipe connections 14 and 34 and by-passes 35 and 36 under the control of the 95 valves 37 and 38, the feed piston and guide sheave 33 being in the position shown by full lines in Fig. 1. As the cutting bit deepens the hole fluid is by-passed, through the connection 41 and under the control of the valves 100 39 and 40, from the forward end of the cylinder 24 to the rear end of the cylinder and the diamond bit is gradually fed toward the work, the hydraulic feed relieving excessive weight from the bit. It will herein be noted 105 that there is a substantial speed reduction between the "fast line" of the hoisting mechanism and the rod line due to the pulley blocks and multi-strand connection, for instance, if the feed piston has a travel of several feet, the 110 rod line will be fed only a few inches. This feeding movement is continued until the "fast line" of the cable and the pulley 33 assume the position indicated by dotted lines in Fig. 1. To obtain further feed the cable is slackened up from the drum 5 and the piston 30 reversed in the cylinder until it again assumes the position indicated by full lines in Fig. 1, the above operations being repeated until a 115 hole of the desired depth is obtained. As the bit penetrates the subterraneous formations desired control of the grief stem is obtained by suitable adjustment of the valves 37, 38, 39, and 40. When it is desired to drain the cylinder 24 the valves 37 and 38 are closed and the valves 39, 40 and 42 are opened and the water is then allowed to flow from the cylinder through the drain pipe 43. 120

As a result of my improved hydraulic feeding and controlling device the usual rotary oil 125 130

or gas well drilling apparatus is enabled to be utilized with a core barrel and diamond cutting bit. It will further be noted that improved hydraulic feeding means is provided which acts directly on the "fast line" of the hoisting cable and by which all necessity of fastening and loosening rope clamps or the like is eliminated. It will further be noted that improved hydraulic feeding means is provided for a rotary drilling rig which acts directly on the "fast line" of the usual hoisting cable whereby the hoist can be operated instantly without disconnecting the hydraulic therefrom. These and other advantages of my invention will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rotary oil or gas well drilling apparatus, the combination with a rotary table, rod line, and hoisting mechanism including a hoisting drum and a hoisting cable supporting the rod line, of means for feeding and controlling the rod line including an auxiliary feeding device having means engaging the hoisting cable intermediate the ends thereof, the connection between the hoisting drum and rod line on which the feeding device acts being deflected upon initial feeding of said device and being slackened during feeding until it assumes a straight line when the limit of feed of said device has been reached, said connection being so arranged that a predetermined feeding movement of the feeding device effects a substantially reduced feeding movement of the rod line.

2. In a rotary oil or gas well drilling apparatus, the combination with a rotary table, rod line, and hoisting mechanism including a hoisting drum and a hoisting cable supporting the rod line, of means for feeding and controlling the rod line including an auxiliary feeding device having means engaging the hoisting cable intermediate the ends thereof and relative to which said hoisting cable is movable during the feeding operation, the connection between the hoisting drum and rod line on which the feeding device acts being deflected upon initial feeding of said device and being slackened during feeding until it assumes a straight line when the limit of feed of said device has been reached, said connection being so arranged that a predetermined feeding movement of the feeding device effects a substantially reduced feeding movement of the rod line.

3. In a rotary oil or gas well drilling apparatus, the combination with a rotary table, rod line, and hoisting mechanism including a hoisting drum and a hoisting cable supporting the rod line, of means for feeding and controlling the rod line including an auxiliary feeding device having a sheave engaging the hoisting cable intermediate the ends thereof, the connection between the hoisting drum and rod line on which the feeding device acts being deflected upon initial feeding of said device and being slackened during feeding until it assumes a straight line when the limit of feed of said device has been reached, said connection being so arranged that a predetermined feeding movement of the feeding device effects a substantially reduced feeding movement of the rod line.

4. In a rotary oil or gas well drilling apparatus, the combination with a rotary table, rod line, and hoisting mechanism including a hoisting drum and a hoisting cable supporting the rod line, of means for feeding and controlling the rod line including an auxiliary hydraulic feeding device including a feed cylinder and a piston reciprocable therein and a sheave carried by said piston and engaging the hoisting cable intermediate the ends thereof, the connection between the hoisting drum and rod line on which the feeding device acts being deflected upon initial feeding of said device and being slackened during feeding until it assumes a straight line when the limit of feed of said device has been reached, said connection being so arranged that a predetermined feeding movement of the feeding device effects a substantially reduced feeding movement of the rod line.

In testimony whereof I affix my signature.

JOSEPH S. MITCHELL.
